(57) **ABSTRACT**

A new and distinct variety of *Phalaenopsis* plant named 'PHALFAREN', particularly characterized by having purple flowers with a small light purple edge and dark red lip, 1 to 2 peduncles that are long and sturdy, leaves that are oblong, and is propagated by meristem tissue culture, is disclosed.

3 Drawing Sheets

1

Genus and species: *Phalaenopsis* hybrid.
Variety denomination: 'PHALFAREN'.

BACKGROUND OF THE NEW PLANT

The present invention relates to a new and distinct cultivar of *Phalaenopsis* plant, botanically known as *Phalaenopsis* hybrid of the Orchidaceae family, commonly referred to as moth orchid, and hereinafter referred to by the variety name 'PHALFAREN'.

The new *Phalaenopsis* plant is a product of a planned breeding program conducted by the inventor in Bleiswijk, The Netherlands. The objective of this breeding program was to create a new *Phalaenopsis* plant with attractive and unique dark purple flowers with a small light purple edge and dark red lip, suitable for potted plant production.

The new *Phalaenopsis* plant 'PHALFAREN' is a result of cross-pollination made by the inventor in August 2007 in Bleiswijk, The Netherlands of the proprietary female, or seed parent, *Phalaenopsis* hybrid '01-1434' (unpatented) with the proprietary male, or pollen parent, *Phalaenopsis* hybrid '01-2114' (unpatented).

The new *Phalaenopsis* was selected by the inventor as a single plant within the progeny of the stated cross-pollination in a controlled greenhouse in Bleiswijk, The Netherlands in August 2010. Asexual reproduction of the new *Phalaenopsis* plant by meristem tissue culture since 2013 in Bleiswijk, The Netherlands, has demonstrated that the new variety reproduces true to type with all of the characteristics, as herein described, firmly fixed and retained through successive generations.

Plant Breeder's Rights for this variety have been applied for in Europe on Apr. 25, 2017. 'PHALFAREN' has not been made publicly available or sold anywhere in the world more than one year prior to the effective filing date of this application.

SUMMARY OF THE INVENTION

The following are the most outstanding and distinguishing characteristics of this new cultivar when grown under

2

normal horticultural practices in Bleiswijk, The Netherlands and can be used to distinguish 'PHALFAREN' as a new and distinct variety of *Phalaenopsis* plant.

- 1) Purple flowers with a small light purple edge and dark red lip;
2) 1 to 2 peduncles;
3) Peduncle is long and sturdy; and
4) Shape of the leaf is oblong.

DESCRIPTION OF THE PHOTOGRAPHS

This new *Phalaenopsis* plant is illustrated by the accompanying photographs which show the overall plant habit including blooms and foliage of the plant; the colors shown are as true as can be reasonably obtained by conventional photographic procedures. The photographs were taken in a greenhouse in Bleiswijk, The Netherlands, from 50-week old plants in July 2017. Colors in the photographs may differ from the color values cited in the detailed botanical description, which accurately describe the actual colors of the new variety.

FIG. 1 shows the overall plant habit, including blooms and foliage of 'PHALFAREN'.

FIG. 2 shows a close-up of a flower of 'PHALFAREN'.

FIG. 3 shows a close-up of the leaves of 'PHALFAREN'.

DESCRIPTION OF THE NEW VARIETY

The following detailed description sets forth the distinctive characteristics of 'PHALFAREN'. Plants of the new *Phalaenopsis* have not been observed under all possible environmental conditions. The phenotype may vary somewhat with variations in environment such as temperature, light intensity and day length, without, however, any variance in genotype. The chart used in the identification of colors described herein is The R.H.S. Colour Chart of The Royal Horticultural Society, London, England, 2015 edition, except where general color terms of ordinary significance

are used. The color values were determined under 4000-6000 lux natural light in a greenhouse in Bleiswijk, The Netherlands. Observations and measurements were made in July 2017 on 50-week old plants which were planted from a nursery tray in 12 centimeter (diameter) pots and grown in a greenhouse between 27° C. to 29° C. for 30 weeks, continued by a cooling period of 8 weeks between 18° C. to 20° C. and 12 weeks in a greenhouse of 21° C.

DETAILED BOTANICAL DESCRIPTION

Classification:

Family.—Orchidaceae.

Botanical.—*Phalaenopsis* hybrid.

Common name.—Moth orchid.

Variety name.—‘PHALFAREN’.

Parentage:

Female parent.—*Phalaenopsis* cultivar ‘01-1434’ (unpatented).

Male parent.—*Phalaenopsis* cultivar ‘01-2114’ (unpatented).

Propagation:

Type.—Meristem tissue culture.

Roots:

Root description.—Greyed-green colored roots (RHS 190B/C) with branching lateral roots having dark red colored root tips (RHS 183B).

Plant:

Commercial crop time to flowering.—Approximately 48 to 50 weeks from a rooted cutting to finish in a 12 cm pot.

Growth habit of peduncle.—Standard, green leaves, raceme to panicle.

Height (from soil level to top of inflorescence).—Approximately 59.0 cm to 64.0 cm.

Width (measured from leaf tips).—About 41.0 cm to 43.0 cm.

Vigor.—Moderate.

Leaves:

Mature leaves.—Quantity per plant: 7 to 9 leaves are produced before flowering. Length (fully expanded): 21.0 cm to 23.0 cm. Width: 8.0 cm to 9.0 cm. Shape: Oblong. Base shape: Moderately elongated to very elongated. Apex: Obtuse unequal. Leaf blade angle with the petiole (measured from the horizontal position): Between 20 degrees and 30 degrees. Leaf margin: Entire. Color: Upper surface: RHS 146A. Lower surface: RHS 146B and RHS 187A at the margin. Texture: Rough. Thickness: 2.5 mm to 2.7 mm. Venation: Pattern: Parallel. Color of the mid-vein: Upper surface: RHS 146A. Lower surface: RHS 146B.

Peduncle:

Quantity per plant.—1 to 2.

Number of flowers per peduncle.—10 to 14.

Length.—59.0 cm to 64.0 cm.

Diameter.—6.5 mm to 6.8 mm.

Strength.—Moderate.

Aspect.—Upright to slightly pendant.

Texture.—Smooth.

Color.—Mix of brown (RHS 200C) and green (RHS 146B/C).

Internode length.—3.0 cm to 4.0 cm.

Callosities.—None.

5

Inflorescence description:

Appearance.—Upright to slightly pendant, raceme to panicle inflorescence with bilaterally symmetrical flowers that open in succession beginning with the lowermost flower.

Inflorescence size.—Height (from base to tip): 240.0 mm to 290.0 mm.

Flowering time.—First flowers can be expected 10 to 11 months after planting in a 12 cm (diameter) pot.

Flower.—Height: 71.0 mm to 76.0 mm. Diameter: 85.0 mm to 90.0 mm. Depth of lip: 22.0 mm to 24.0 mm.

Flower longevity.—On the plant: 8 to 12 weeks.

Fragrance.—Absent.

Flower bud.—Average size: Medium to large. Length: 20.0 mm to 22.0 mm. Width: 18.0 mm to 20.0 mm.

Shape: Egg shaped. Color: Green (RHS 146D) with diluting dark red-purple shade (RHS N79B and 187B).

Petals.—Arrangement: Open/free. Shape: Semi-circular. Apex: Rounded asymmetric. Margin: Entire. Length (from base to tip): 40.0 mm to 42.0 mm. Width: 52.0 mm to 54.0 mm. Color (when fully opened): Upper surface: Basic color: Purple (RHS N78A). Over color: Light purple edge (RHS 76B). Lower surface: Basic color: Purple (RHS N78C). Over color: Light purple (RHS 76A).

Dorsal sepal.—Shape: Elliptic. Apex: Obtuse symmetric. Margin: Entire. Length (from base to tip): 40.0 mm to 42.0 mm. Width: 27.0 mm to 29.0 mm. Color (when fully opened): Upper surface: Basic color: Purple (RHS N78A). Over color: Red-purple (RHS N79C) in the middle. Lower surface: Basic color: Purple (RHS N78C). Over color: Light purple (RHS 76B).

Lateral sepals.—Shape: Ovate. Apex: Obtuse asymmetric. Margin: Entire. Length (from base to tip): 42.0 mm to 44.0 mm. Width: 25.0 mm to 27.0 mm. Color (when fully opened): Upper surface: Basic color: Purple (RHS N78A). Over color: Light green (RHS 145D) at the base and red-purple spots (RHS N79C). Lower surface: Basic color: Purple (RHS N78C). Over color: Light purple (RHS 76A).

Labelum (lip).—Whiskers: Present. Length of whiskers: 12.0 mm to 14.0 mm. Color of whiskers: Dark red-purple (RHS N79A and 187A). Pubescence on the lip: Absent.

Lateral lobe.—Shape: Spatulate. Margin: Slightly undulated. Length: 21.0 mm to 23.0 mm. Width: 14.0 mm to 16.0 mm. Color: Yellow (RHS 13B) at the base; dark red (RHS 59A) and dark red-purple (RHS N79C) toward the margin; white edge (RHS NN155C) toward the column.

Apical lobe.—Shape: Triangular. Margin: Entire. Length: 21.0 mm to 23.0 mm. Width: 20.0 mm to 22.0 mm. Color: Dark red (RHS 187A/B) and slightly yellow (RHS 13C) at the base.

Callus.—Height: 8.0 mm to 10.0 mm. Length: 6.0 mm to 8.0 mm. Width: 4.0 mm to 6.0 mm. Color: Yellow (RHS 13A); lighter yellow (RHS 10B) on sides; dark red spots (RHS 187A).

Reproductive organs:

Column.—Length: 8.0 mm to 10.0 mm. Diameter: 5.6 mm to 5.8 mm. Color: Purple (RHS N78A).

Pollinia.—Quantity: 2. Diameter: 1.2 mm to 1.4 mm. Color: Orange (RHS 26A).

Ovary.—Length: 6.0 mm to 8.0 mm. Diameter: 1.9 mm to 2.1 mm.

Pedicel.—Length: 29.0 mm to 31.0 mm. Diameter: 2.5 mm to 2.7 mm. Color: Green (RHS 145D) and light purple (RHS N78D).

Disease, pest, and stress resistance: No specific resistance or susceptibility observed to pathogens and pests common to *Phalaenopsis* to date.

Fruit and seeds: Fruit and seed development has not been observed on plants of the new *Phalaenopsis* to date.

COMPARISON WITH PARENTAL LINES AND MOST SIMILAR VARIETIES

The female and male parent plants of 'PHALFAREN' are no longer in existence, so a meaningful comparison cannot be made.

'PHALFAREN' is most similar to the commercial *Phalaenopsis* plants named 'PHALUFREL' (U.S. Plant Pat. No.

29,259) and 'PHALDANBO' (U.S. Plant Pat. No. 25,930). 'PHALFAREN' differs from the commercial variety 'PHALUFREL' in that 'PHALFAREN' has a small edge flower pattern, whereas 'PHALUFREL' has a broad edge flower pattern. Additionally, 'PHALFAREN' has longer whiskers, longer lateral sepals and narrower dorsal sepals than 'PHALUFREL'.

'PHALFAREN' differs from the commercial variety 'PHALDANBO' in that 'PHALFAREN' has a rounded asymmetric petal apex, whereas 'PHALDANBO' has a mucronate and symmetric petal apex. Additionally, 'PHALFAREN' has longer whiskers, longer lateral sepals and narrower dorsal sepals than 'PHALDANBO'.

I claim:

1. A new and distinct variety of *Phalaenopsis* plant named 'PHALFAREN', substantially as described and illustrated herein.
